UNITED STATES PATENT OFFICE.

ANDREW KOESCHE, OF CHICAGO, ILLINOIS, ASSIGNOR TO THE BASTIAN BLESSING COMPANY, OF CHICAGO, ILLINOIS, A CORPORATION OF ILLINOIS.

CARBONATOR.

1,090,157.

Specification of Letters Patent. Patented Mar. 17, 1914.

Application filed June 21, 1913. Serial No. 774,952.

To all whom it may concern:

Be it known that I, ANDREW KOESCHE, a citizen of the United States, residing at Chicago, in the county of Cook and State 5 of Illinois, have invented certain new and useful Improvements in Carbonators, of which the following is a specification.

This invention relates to carbonating apparatus in which carbonic acid gas under 10 pressure is mixed with water or other liquid to produce a carbonated beverage, and has more particular reference to an improved means for automatically controlling the motor which operates the pump and other 15 operative mechanisms of the apparatus.

One of the primary objects of the present invention is the provisions of an improved mechanism adapted to be operated by the 20 gas pressure from the mixing tank for automatically applying the electric current to the operating motor in such a manner that the motor will always start slowly without shock and without imposing undue strains upon the operating parts and will gradually 25 increase in speed until the maximum is reached.

Other objects and many of the attendant 30 advantages of the present invention will be readily apparent to those skilled in the art as the invention becomes better understood by reference to the following description when considered in connection with the accompanying drawings, the single figure of 35 which illustrates in side elevation a carbonating apparatus of standard type equipped with my invention.

Referring to the drawings, 5 designates a tank in which the water and gas are mixed, this tank being supplied with water through 40 a pipe 6 from a reciprocating double-acting pump 7 provided with an inlet pipe 8. The pump may be of any preferred construction, but in the present instance I have shown the pump 7 as a double-acting pump having 45 inlet connections 9 and 11 and discharge connections 12 and 13 respectively.

The piston rod 14 of the pump is connected by a crank-arm 15 with the drive-head 16 of a shaft (not shown) mounted in 50 a suitable standard 17 and carrying on its opposite end a gear wheel 18. An electric motor 19 of any preferred type is equipped

with a driving pinion 21 meshing with and driving the gear wheel 18. The mixing tank is provided with a rotary agitator of 55 any preferred construction which is driven by means of a drive-chain 22 from a sprocket wheel 23 mounted on the main shaft carrying the gear wheel 18.

Gas under pressure is admitted from any 60 suitable source of supply to the mixing tank through a connection 24 or otherwise, and the water from the pump 7 is conducted through pipes 6 and 25 to the top of the mixing chamber 26 and flows downwardly there- 65 in to the mixing tank, while the gas rising in the mixing chamber is thoroughly mixed with the water, the surplus gas being returned to the bottom of the mixing chamber through pipe 27.

A gas pipe 28 is coupled to the connection 29 at the base of the mixing chamber and also to an angle connection on the side of the mixing tank provided with a controlling valve 31, carried by a stem 32 connected to 70 a balanced lever 33 pivotally mounted on a stud 34 projecting from the side of the mixing tank. A balanced tank 35 is suspended from one end of the lever 33 and a weight 36 is suspended from the opposite end. A 75 hose 37 connects the upper end of the balanced tank with the mixing tank and a similar hose 38 connects the lower end of the balanced tank with the mixing tank. By reason of these connecting hose the level of 80 the liquid in the balanced tank always approximates the level of the liquid in the mixing tank. When the balanced tank is approximately full of water it will overbalance 85 the weight 36 and close the gas pipe 28 by 90 means of the valve 31. When, however, a considerable quantity of carbonated liquid has been drawn off from the mixing tank the balanced tank will decrease in weight 95 until it will be overbalanced by the weight 36, whereupon the valve 31 will be opened to admit gas under pressure from the pipe 28 to the pipe 39 leading to my improved controlling device.

The balanced tank and its connections are 100 substantially like those disclosed in Patent No. 932,093, granted to Bastian, August 24, 1909. The pump disclosed in the Bastian patent is hydraulically operated and the

gas pressure in the mixing tank is utilized to operate a controlling valve for the pump. My present invention, on the other hand, contemplates the employment of the gas pressure for controlling an electrically operated pump. I therefore provide a board 41 which may be mounted in any suitable location adjacent the carbonating apparatus and on this board are located a rheostat 42 of usual construction, a pair of line switches 43 pivoted at 44 and a mechanism for automatically operating the switches and the rheostat. The mechanism comprises, in the form of my invention illustrated on the drawings, a cylinder 45 to one end of which is connected the gas pipe 39. Within the cylinder a piston is arranged to reciprocate and the piston rod 46 is guided adjacent its extremity by a guide 47. A coiled expansion spring 48 surrounding the piston rod normally urges the piston in the cylinder toward the lower end where the pipe 39 is attached. A lever 49 is pivotally mounted on the board at 51 and comprises an arm 52 provided with an elongated slot 53, which engages a boss or stud 54 projecting laterally from the piston rod. Another arm 55 rigid with the arms 49 and 52 is connected by a link 56 with a rod 57 attached to the tails of the line switches 43.

When the parts are in the position indicated on the drawing, the line switches are open, the motor is at rest and the balanced tank 35 is in lowered position. When carbonated liquid has been withdrawn from the mixing tank until the weight 36 overbalances the balanced tank, gas under pressure will be admitted to the lower end of the cylinder 45 through the pipes 28 and 39 by operation of the valve 31. The gas pressure within the cylinder 45 will force the piston therein upwardly, thereby swinging the lever 49 about the pivot 51 to first close the line switches 43 and then cause the lever 49 to engage the operating handle 58 and swing this handle consecutively from one button to the next of the rheostat, thereby gradually cutting out the resistance and permitting the motor to speed up. When all of the resistance has been cut out, the handle 58 will be held by the electro-magnet 59 so long as current is applied. When the pump 7 has supplied liquid to the mixing tank and the balanced tank until the balanced tank overbalances the weight 36, the valve 31 will be operated to close the pipe 28 and open pipe 39 to the atmosphere, which will permit the gas to escape from the cylinder 45. The spring 48 will thereupon return the piston to its lower position, thereby opening the line switches and return the lever 49 to normal inoperative position and as soon as the circuit is broken the handle 58 will be returned to inoperative position by a spring in the usual manner.

It is believed that my invention and its mode of operation will be fully understood from the foregoing without further description and it will be manifest that the size, shape, proportion and arrangement of the various parts may be changed within wide limits without departing from the scope of my invention as set forth in the following claims.

I claim:

1. In a carbonating apparatus, the combination of a mixing tank, a pump for supplying water to said tank, a motor for operating said pump, a switch and a rheostat in the motor operating circuit, means operated by gas pressure from the mixing tank for closing said switch and slowly operating said rheostat, and means controlled by the level of the liquid in said tank for controlling the supply of gas to said means. 75
2. In a carbonating apparatus, the combination of a mixing tank, an electrically driven pump for supplying water to said tank, a rheostat and a switch disposed in the pump operating circuit, a pressure actuated device adapted to operate said switch and rheostat, connections for supplying gas under pressure from said tank to said device, means controlled by the liquid level in the tank for controlling the supply of gas to said device, and means for restoring said device to normal position when the gas pressure is released. 80
3. In a carbonating apparatus, the combination of a mixing tank, an electrically operated pump for supplying water thereto, a rheostat and an electric switch located in the pump operating circuit, a pressure actuated device, including a plunger and a pivotally mounted lever adapted to operate said switch and rheostat, a connection for supplying gas under pressure to said device from the mixing tank, and means operated by variation in liquid level in the tank for controlling the supply of gas from the tank to said device. 85
4. In a carbonating apparatus, the combination of a mixing tank, an electrically operated pump, a rheostat interposed in the pump operating circuit, a cylinder mounted adjacent said rheostat, a plunger reciprocal in said cylinder, a pivoted lever connected with the plunger and adapted to operate said rheostat, connections for supplying gas to said cylinder from said mixing tank to move said plunger in one direction, means for controlling the flow of gas to and from said cylinder, and means for returning said plunger to normal inoperative position. 90
5. In a carbonating apparatus, the combination of a mixing tank, an electrically operated pump, a rheostat and a switch disposed in the pump operating circuit, a cylinder, a piston mounted to reciprocate in said cylinder, connections between said piston and 95

said switch, a lever operated from said piston to control the rheostat, a spring normally retaining said switch in open position and said lever in inoperative position with 5 respect to the rheostat, a connection for supplying gas under pressure to said cylinder from the mixing tank to move the piston and thereby close the switch and gradually

operate the rheostat, and means actuated by variations in the liquid level in the tank for 10 controlling the supply of gas to said cylinder.
